ATTORNEY, S.

UNITED STATES PATENT OFFICE.

CHARLES P. WETMORE, OF MILWAUKEE, WISCONSIN, ASSIGNOR TO WETMORE MECHANICAL LABORATORY COMPANY, OF MILWAUKEE, WISCONSIN, A CORPORATION OF WISCONSIN.

RAZOR-BLADE KNIFE.

Application filed April 3, 1922. Serial No. 548,907.

To all whom it may concern:

Be it known that I, CHARLES P. WETMORE, a citizen of the United States, residing at Milwaukee, in the county of Milwaukee and State of Wisconsin, have invented certain new and useful Improvements in Razor-Blade Knives, of which the following is a specification, reference being had to the accompanying drawing, forming a part thereof.

This invention relates to knives for utilizing discarded safety-razor blades.

Its main objects are to provide such a knife with simple effective means for securely but releasably clamping and holding thin safety-razor blades in place for use therein without loose or detachable fastenings; to prevent binding of the clamping leaves next to the blade against the handle, and to subject their contacting faces adjacent their pivot connection to a yielding pressure sufficient to hold the knife open or closed; to facilitate removing and replacing blades; to adapt such a knife to a wider range of uses; to guard the rear corner of the blade and thereby prevent cutting the hand in which the knife is held; and generally to improve the construction and increase the utility or convenience of knives of this class.

It consists in the construction, arrangement and combination of parts as herein-after particularly described and pointed out in the claims.

In the accompanying drawing like characters designate the same parts in the several figures.

Figure 1 is a side elevation of an open knife embodying the invention, a part of the handle being broken away; Fig. 2 is an edge view of the open knife as viewed from the top of Fig. 1, a portion of one of the blade clamping leaves being broken away; Fig. 3 is a longitudinal section of the knife on the line 3—3, Fig. 1; Fig. 4 is a side elevation of the closed knife; and Fig. 5 is an enlarged cross section of the closed knife on the line 5—5, Fig. 4.

The knife comprises a handle preferably made of sheet metal, with spaced parallel sides 1, connected along one side by a fold forming a closed back 2. Adjacent one end the sides are formed with aligned rivet holes, and at the opposite end with inturned flanges 3, closing the outer end of the handle. At the outer end the handle is provided with a ring 4, for attaching the knife to a chain if desired. Adjacent the outer end the sides 1 are formed with aligned cigar openings 5, and with thumb notches 6 in the edges opposite the back 2.

The knife is provided with a blade holder consisting of two clamping leaves 8 and 9, which are formed with outwardly offset shanks or pivot ends 10. The shanks or ends 10 are formed with aligned circular holes fitted to turn on a spacing washer 11, fastened between the handle sides 1 by a rivet 12, preferably of tubular form, which is flanged or upset at the ends to bind the handle sides together against the ends of the washer 11. The shanks or pivot ends 10 of the clamping leaves are normally spaced by the offsets therein, so that the distance between their outer faces is slightly greater than the distance between the inner faces of the sides 1 of the handle. The outer faces of the shanks or pivot ends 10 are thus made to exert a yielding pressure against the inner faces of the handle sides 1, sufficient to effectively retain the blade holder with a blade clamped therein, either open as shown in Fig. 1, or closed as shown in Fig. 4.

The leaf 8 is formed along its back edge with an inturned gage and stop flange 14, and at its outer end with a hooked clip 15.

The leaf 9, which is made of spring or resilient metal, is normally bowed lengthwise towards the leaf 8, as shown in Fig. 3, and is concaved on the inner side crosswise, as shown in Fig. 5, so that when it is pressed against a razor blade 17, positioned on the leaf 8, with one edge against the flange 14, and is turned at its outer end into engagement with the clip 15, it will exert a uni-

form clamping pressure the full length of its edges against the blade and securely hold the same in place between it and the leaf 8, with the edge of the blade opposite the flange 14 exposed, as shown in Fig. 1.

The leaves 8 and 9 are preferably gradually chamfered or beveled on the outer sides along their front edges adjacent the exposed cutting edge of the blade 17, as shown in Figs. 1 and 5, and adjacent their inner ends they are extended transversely to form guards 19 for the rear or inner corner or end of the cutting edge of the blade, as shown in Fig. 1, and thus protect the finger 15 of the hand in which the knife is held.

The offset shank or pivot end 10 of the leaf 9 is formed as shown in Figs. 1 and 2, with an inwardly struck ear or lug 21, which by engagement with the inner end of a blade 17 when clamped in position between the leaves 8 and 9, holds it against being pulled away from the flange 14, particularly when pressure is applied to the cutting edge of the blade at or adjacent its opposite end.

25 The leaf 8 is formed at its outer end adjacent the flange 14 with a nail cleaning prong or spur 23, and both leaves are formed on their outer sides with nail files and finger grips 24, the knife being thus adapted for 30 manicure uses. These files and finger grips are preferably located so that they are exposed when the knife is closed, through the openings 5, and may then be used as finger grips to facilitate opening the knife. They 35 also facilitate the manipulation of the leaves 8 and 9 when the knife is open, for removing and replacing blades.

The flange 14, by abutment at its inner end with the adjacent end of the back 2, as shown 40 in Fig. 1, serves as a stop to hold the clamping leaves 8 and 9 with a blade 17, clamped between them, in alignment with the handle. It also serves, as shown in Fig. 4, by engagement with the notched edge of one of the 45 handle sides 1, to limit the closing movement of the blade holder and blade, and in connection with the adjacent notch 6, as a thumb nail catch or hold for opening the knife.

When a blade is clamped between the leaves 50 8 and 9, as shown in Figs. 1, 2 and 5, the outward pressure of the shanks or pivot ends 10 of the leaves 8 and 9 against the inner faces of the handle sides 1, reacts through the leaves to firmly clamp and hold the blade 55 between them, the shoulders formed by the offsets in the leaves acting as fulcrums against each other or against the adjacent end of the blade, and tending to spread the shanks or pivot ends 10 and to separate the 60 leaves.

The resiliency of the inwardly bowed spring leaf 9, exerting an outward pressure against the clip 15 with which it is engaged and which serves as an end positioning abutment for a blade, in connection with the

flange 14 which serves as a back abutment, and the ear or lug 21, which serves as an inner end abutment for the blade, securely holds the leaves with the blade clamped between them, in place.

To cut the tip end from a cigar with the knife, the tip of the cigar is inserted in the opening 5 in one side of the knife when it is opened or partially opened, the blade is then closed and pressed with the clamping leaves 75 into the handle, thereby severing the cigar tip, which falls through the opening in the other side of the handle.

I claim:

1. In a razor-blade knife the combination 80 of a handle having spaced sides and blade-clamping leaves one of which is resilient, pivotally connected with each other and with the sides of the handle and outwardly offset to exert a yielding outward pressure 85 against the sides of the handle adjacent their pivot connection therewith and to react with a clamping pressure on the adjacent end of an interposed blade.

2. In a razor-blade knife the combination 90 of a handle having spaced sides, a spacing washer interposed between the sides of the handle adjacent one end thereof, a rivet passing through the washer and binding the sides 95 of the handle together, and blade-clamping leaves one of which is resilient, having outwardly offset ends pivotally mounted on said washer and exerting against the inner faces of the handle sides an outward pressure which reacts with an inward pressure to 100 clamp an interposed blade between adjacent parts of the leaves.

3. In a razor-blade knife, the combination 105 of a sheet metal handle formed with spaced parallel sides, a connecting back fold and end flanges closing one end, and a blade holder composed of two clamping leaves one of which is resilient, having outwardly offset ends pivotally connected with each other and with the sides of the handle, one of the leaves having an inturned flange along its back edge and at its outer end an inturned clip under which the other leaf is adapted to be sprung for clamping a blade between them.

4. In a razor-blade knife, the combination 115 of a handle having spaced sides and a closed back connecting the sides, and a blade holder composed of two clamping leaves having outwardly offset ends pivoted to each other and to and between the sides of the handle, one of the leaves being resilient, concave cross-wise on the inner side and normally bowed lengthwise towards the other, which is formed along its back edge with an inturned flange adapted to abut at one end against the adjacent end of the handle back and to hold the blade in alignment with the handle when the knife is opened, and one leaf being provided at its outer end with a clip with which the other leaf is adapted to be engaged when 120 125 130

turned on its pivot to clamp a blade between them throughout its entire length along the edges of the concave leaf.

5. In a razor-blade knife the combination of a handle having spaced sides connected along the back and provided with inturned flanges forming a closed end, a spacing wash-

er interposed between and fastened to the sides adjacent the other end, and a blade holder pivotally mounted on the washer. 10

In witness whereof I hereto affix my signature.

CHARLES P. WETMORE.
